UNITED STATES PATENT OFFICE

DAVID J. BINUS, OF CANTON, OHIO, ASSIGNOR TO THE WEBER DENTAL MANUFACTURING COMPANY, OF CANTON, OHIO, A CORPORATION OF OHIO

ROLLER GUIDE

Application filed August 13, 1929. Serial No. 385,616.

My invention relates to roller guides more particularly for use in connection with the telescoping sleeves of dental chair elevators and the like.

Such elevators may include a plurality of telescoping sleeves or housing sections, and it is necessary to prevent the sleeves from rotating with respect to each other in order to maintain the required longitudinal alignment of the elevator parts, and it has been found that mere interfitting sliding guides are difficult and expensive to manufacture, and are subject to excessive friction, causing wear of the sliding surfaces, and are furthermore very difficult to provide with suitable adjusting means for taking up the wear.

Accordingly the objects of the present invention includes the provision of improved roller guides for use between two members longitudinally movable with respect to each other, such as the telescoping housing sections of a dental chair elevator, and to provide novel adjusting means for such roller guides.

These and ancillary objects are attained in the present invention, as will hereinafter be set forth in detail and claimed, and which may be stated in general terms as including the combination with two members longitudinally movable with respect to each other of a longitudinally extending rail preferably removably secured on one member, one or more shafts mounted on the other member and extending cross-wise of the rail, and a pair of preferably conically shaped rollers rotatably mounted on each shaft with the apexes of the rollers adjacent each other for rolling on opposite sides of the guide member, anti-friction thrust bearings for the rollers, and means for adjusting the spacing of the rollers on the shaft.

A preferred embodiment of the invention is illustrated in the accompanying drawings forming part hereof, in which

Figure 1 is a fragmentary elevation view of a telescopic elevator for a dental chair or the like, portions of the intermediate telescopic member of the elevator being broken away and illustrated in section on the vertical plane

50 A passing through the axes of the roller

guide shafts at one side of the intermediate member and looking in the direction of the arrows a—a, Fig. 2, and portions of the lower telescopic member of the elevator being broken away and illustrated in section on the vertical plane B passing through the axes of the roller guide shafts at one side of the lower telescopic member and looking in the direction of the arrows b—b, Fig. 2; and

Fig. 2, a fragmentary plan view thereof, portions being broken away and illustrated in section on the horizontal plane C passing through the opposite upper roller guide shafts of the intermediate telescopic member and looking in the direction of the arrows c—c, Fig. 1, and portions being broken away and illustrated in section on the horizontal plane D passing through the axes of the opposite upper roller guide shafts of the lower telescopic member and looking in the direction of the arrows d—d, Fig. 1.

Similar numerals refer to similar parts throughout the drawings.

The dental chair elevator indicated generally at 10, includes a base 11, a lower telescopic member 12 supported by the base, an intermediate telescopic member 13 longitudinally telescoping within the lower member 12, and an upper telescopic member 14 longitudinally telescoping within the intermediate member 13.

At the upper end of the upper member 14, the seat 15 of a dental chair may be supported.

All of the foregoing members are hollow, and house suitable mechanism not shown, but which may be that illustrated in the prior application for patent of Henry E. Weber, for dental chair elevators, filed November 3, 1928, Serial No. 316,969, which matured into Patent No. 1,814,874, issued July 14, 1931 whereby the telescopic members may be raised by operation of an elevating pedal lever 16, and may be lowered by operation of a lowering pedal lever 17.

In raising and lowering the telescopic members of the elevator, it is necessary to prevent rotary movement of the members with respect to each other.

One member of each pair of the telescopic

ing members is provided preferably at opposite sides with longitudinally spaced sets of roller members and their adjustable mountings, each set being illustrated generally at 20, and each set comprising one cooperating instrumentation of the improved roller guide hereof.

For example, the upper set of roller members and mountings 20 on the intermediate member 13, as viewed in Fig. 1, will be described in detail, each of the other sets being of substantially identical construction.

This set together with the longitudinally spaced lower set at that side of the intermediate member 13 cooperates with a longitudinally extending rail 21 which is preferably a circular rod, removably secured as by screws 22 in an outer groove formed in the upper telescopic member 14.

A similar rail 21 is mounted on the upper member 14 opposite the first mentioned rail, and similar opposite rails are secured in longitudinally extending grooves on the outer surface of the intermediate member 13 and cooperate with longitudinally spaced sets of the roller members and adjustable mountings 20 secured in opposite sides of the lower member 12.

Referring to the particular set 20 under consideration, the intermediate member 13 has formed therein a horizontal laterally extending bore 23. The bore 23 is threaded at its central portion 24 and the walls of the member 13 have an inner side opening 25 formed therein, communicating with the inner end of the bore, and into which side opening the rail 21 extends.

The bore 23 is provided with an inner end extension 26 of substantially reduced diameter, and the inner bore extension 26 forms a bearing for one end of a roller shaft 27.

The roller shaft 27 extends transversely cross-wise of the rail 21 and its other end is supported in a bearing bore 28 formed in a screw plug 29 which is adapted to screw in the threaded central portion 24 of the bore 23.

At opposite sides of the rail 21 preferably conical rollers 30a and 30b are rotatably mounted, with their apexes adjacent each other and with their conical surfaces rolling against opposite sides of the rail 21.

A preferably anti-friction thrust bearing 31a is interposed between the base end 32a of the conical roller 30a and one surface of a thrust disk 33a which is seated against the shoulder 34a formed between the inner end of the enlarged bore 23 and the reduced extension 26.

Similarly a preferably anti-friction thrust bearing 31b is interposed between the base end 32b of the conical roller 30b and a thrust disk 33b which is seated against the inner end of the screw plug 29.

By screwing the plug 29 towards or away

from the roller members, the distance between their opposite conical surfaces is decreased or increased, and the rollers are arranged to roll longitudinally on the rail with no sliding friction, forming the improved 70 adjustable roller guide hereof.

Any wear on either the rail or the rollers may be taken up by suitable adjustment of the screw plug 29.

A set screw 35 screwed in a suitable aperture in the member 13 and engaging with the screw plug 29 secures the set of roller members in any desired position of adjustment.

A filler plug 36 may be provided if desired 80 for the outer end of the bore 23.

I claim:—

1. In combination, two telescopic members longitudinally movable with respect to each other, a longitudinally extending rail secured on one member, spaced rollers movable with respect to each other and rotatably mounted on the other member, and means for moving said rollers with respect to each other thereby maintaining opposite faces of the 90 rollers in rolling contact against opposite sides of the rail.

2. In combination, two telescopic members longitudinally movable with respect to each other, a longitudinally extending rail secured 95 on one member, a shaft mounted on the other member and extending transversely of the rail, spaced rollers rotatably mounted on the shaft and rolling against opposite sides of the rail, and means for adjusting the spacing 100 of the rollers on the shaft.

3. In combination, two telescopic members longitudinally movable with respect to each other, a longitudinally extending rail secured on one member, a shaft mounted on the other member and extending transversely of the rail, spaced rollers rotatably and slidably mounted on the shaft and rolling against opposite sides of the rail, and means for sliding said rollers on said shaft toward 110 each other.

In testimony that I claim the above, I have hereunto subscribed my name.

DAVID J. BINUS.
